J. M. WILLS

DEVICE FOR SUPPORTING AND OPERATING LIFTING JACKS

Filed Oct. 15, 1923

FIG. 1.

卷之二

2009.3.

INVENTOR

JAMES M. WILLS

BY William S. Fowler
ATTORNEY

UNITED STATES PATENT OFFICE.

JAMES M. WILLS, OF OTTAWA, ONTARIO, CANADA.

DEVICE FOR SUPPORTING AND OPERATING LIFTING JACKS.

Application filed October 15, 1923. Serial No. 668,630.

To all whom it may concern:

Be it known that I, JAMES M. WILLS, a citizen of the Dominion of Canada, and resident of Ottawa, in the county of Carleton and Province of Ontario, Dominion of Canada, have invented certain new and useful Improvements in Devices for Supporting and Operating Lifting Jacks, of which the following is a specification.

- 10 This invention has relation to certain new and useful improvements in devices for supporting and operating lifting jacks and has for its primary object the provision of devices of the character stated which will be of 60
15 simple and compact construction, easy to manipulate and which will make it possible to operate the lifting jacks from a distance, thereby making it unnecessary to have the operator to be positioned close to the lifting 65
20 jacks when they are placed under motor vehicles and the like.

Another object resides in the provision of a device of the character stated which may be employed in connection with various forms 25
25 of lifting jacks and may be readily connected with the lifting jacks or detached from the same and folded into compact form with the various parts of the device held 70
30 against independent movement when not in use.

The invention has for a further object the provision of a device of the character stated which will be constructed so as to rest securely on the ground or other surface with 35
35 the operating rod and handle firmly supported in operative position during use of the device and the supporting portion of the device held firmly in position by the lifting jack resting thereon.

40 With the foregoing and other objects in view as will appear as the description proceeds, the invention consists in the novel construction, combination and arrangement of cooperating elements as hereinafter more 45 specifically set forth, claimed and shown in the accompanying drawings forming a part of the present application, in which:

Fig. 1 is a side elevation of the device, in use.

50 Fig. 2 is a plan view of the device in folded position.

Fig. 3 is a side elevation of the device in folded position.

55 Referring more in detail to the drawings in which similar reference characters designate corresponding parts throughout the sev-

eral views, it will be seen that the device includes a pan or tray 5 to receive the base of the lifting jack 6 of conventional form. While the device may be employed in connection with any form of lifting jack desired, I have illustrated the device as being employed on a lifting jack of the form disclosed in my Canadian Patent 227,067 of December 12th, 1922.

Extending from the pan or tray 5 is a supporting or base member 7 in the form of a channel bar and having a depressed portion 8 while the main part of the channel bar 7 is raised between the portion 8 thereof and the pan or tray 5. The channel bar 7 includes an inclined portion 9 extending from the depressed portion 8 and connecting with the upwardly offset free end 10 which is flattened and bevelled or tapered toward its free extremity 11 so as to serve as a tire removing tool, when required and as will be later understood. It is also to be noted from the drawings that a set screw 12 is extended through the upstanding flange 13 of the pan or tray 5 to secure the latter permanently on the base of the lifting jack 6. A set screw 14 is extended through the upstanding flange 15 of the channel bar 7, adjacent the pan or tray 5 and on one side of the channel bar 7, opposite and inwardly pressed extension 16 which is carried on the upstanding flange 15 at the other side of the channel bar 7. The purpose of the set screw 14 and the inwardly pressed extension 16 will later appear.

50 A standard 17 is pivoted at its lower end on the pivot pin 18 extended through the inclined portion 9 of the channel bar 7. As shown by the drawings, the standard 17 is formed of a comparatively short section of channel iron and flared at its lower end. The upstanding side flanges of the inclined portion 9 are pressed in so that when the standard 17 is moved on the pivot pin 18 to upright position, the pressed in side flanges of the upstanding portion 9 will engage the flared lower end of the standard 17 and firmly grip the same so as to retain the standard 17 in upright position. When the standard 17 is turned or swung forwardly and downwardly on the pivot pin 18 to its lowermost position, the lower end of the standard 17 will be released and the upper or forward end thereof will be gripped by the inwardly pressed gripping portions 19 of the upstanding side flanges.

15 of the channel bar 7. It is therefore apparent that the upper forward end of the standard 17 rests in the channel bar 7 when the standard 17 is in its lowermost or folded position. A ring 20 is mounted on the pivot pin 20* carried in the upper end of the standard 17 and extended transversely thereof in such a manner as to permit the ring 20 to be supported on the upper end of the 10 standard 17 as shown in Fig. 1 or move readily to a position at an angle to the standards 17, as shown clearly in Fig. 3, as the standard 17 is moved to its folded position. The operating rod 21 of the 15 device is extended through the ring 20 and provided on its forward end with a suitable socket 22 to receive the end of the jack operating shaft 23. A set screw 29 is carried by the socket 22 to securely fasten the 20 latter on the end of the jack operating shaft 23. An operating cross handle 25 is firmly fastened on the rear end of the operating rod 21 to serve as the means by which the operating rod 21 may be readily rotated 25 in either direction to operate the lifting jack 6. Handle grips 26 are carried on the end portions of the operating cross handle 25 and a suitable means is employed for retaining the operating cross handle 25 in 30 proper position on the operating rod 21. This means may be in the form of a wing nut 27 as illustrated or in any other suitable form.

It is believed the complete construction 35 and operation of the device may now be apparent from the foregoing paragraphs taken in connection with the accompanying drawings without further detail description. It may be briefly stated, however, that when 40 the device is not in use, the operating rod 21 is positioned in the channel bar 7 with the socket 22 resting in the pan or tray 5 while the rear end portion of the operating rod 21 rests on the end portion 10 of the channel 45 bar 7. The set screw 14 is tightened against the operating rod 21 to hold the same beneath the inwardly pressed extension 16, as shown clearly in Fig. 2. The device is then ready for transportation or for storage 50 in a restricted space.

When it is desired to employ the device for supporting and operating lifting jacks, the set screw 14 is loosened and the operating rod 21 moved to its horizontal or operative position above the channel bar 7 and substantially parallel therewith. In moving the operating rod 21 to this position the standard 17 assumes its operative or upright position, as shown in Fig. 1 and in 55 which position the standard 17 is firmly held by the inclined portion 9 of the channel bar 7 as previously stated in detail. It is therefore evident that a firm and solid support is provided for the operating rod 21 and 60 after attachment of the socket 22 to the member and adapted at times to rest in in-

member to be operated of the lifting jack 6 or other device resting in the pan or tray 5, the operating rod 21 may be readily rotated in either direction by means of the operating cross handle 25. The pan or tray 5 should be firmly held in position by the set screw 12 or other means provided for this purpose so as to securely lock the device with the member resting in the pan or tray 5. The depressed portion 8 of the channel 75 bar 7 will rest firmly on the surface on which the pan or tray 5 is placed even though the portion of the channel bar 7 between the pan or tray 5 and the depressed portion 8 may not rest upon the surface. 80 This will permit use of the device on uneven or stoney surfaces without interfering with the efficiency of the device.

By forcing the operating rod 21 forwardly after the operating cross handle 25 is out of the way of the end portion 10 of the channel bar 7 and moving the standard 17 to its folded or inoperative position, the device may be employed as a tire remover or replacer, owing to the formation of the end 90 portion 10. If desired, the wing nut 27 may be removed and then the operating cross handle 25 withdrawn from the operating rod 21 and the latter removed from the ring 20 when employing the device as a tire remover or replacer or whenever it is desired to separate the parts of the device.

While the preferred embodiment of the invention has been disclosed, it is to be understood that minor changes in the details 100 of construction, combination and arrangement of co-operating elements may be resorted to within the scope of what is claimed without departing from the spirit of the invention.

What I claim as new is:

1. A device for operating lifting jacks including a base member; a jack receiving tray carried at one end of said base member; the opposite end of the base member being offset upwardly and flattened; a standard pivoted to said base member and adapted to be held thereby in upright position; a ring pivotally carried by said standard; an operating rod extending through said ring 115 and adapted to operate therein; said operating rod being adapted for detachable connection with the operating member of the jack for operating the latter; and an operating cross handle carried by said operating 120 rod; said operating rod being adapted when in inoperative position to rest on the flattened end portion of the base member.

2. A device for operating lifting jacks including a base member in the form of a 125 channel bar with one end offset upwardly and flattened; a jack receiving tray carried at the other end of the base member; a standard pivotally connected with said base member and adapted at times to rest in in-

operative position therein; said standard being adapted to be retained at times in up-standing operative position by said base member; a ring pivotally carried by said standard; an operating rod working in said ring; one end of said operating rod being adapted for detachable connection with the operating shaft of a jack supported in the tray; an operating handle carried by said operating rod; and means for preventing movement of the jack in said tray; the oper-
5 ating rod being adapted to rest in the base member when not in position for operation; one end of the operating rod resting in the tray while the other end rests on the up-
wardly offset and flattened end of the base member; said base member carrying means 15 to secure the operating rod in inoperative position in said base member.

In testimony whereof, I affix my signa- 20
ture.

JAMES M. WILLS.
